UNITED STATES PATENT OFFICE.

HARRY IRWIN JEFFERS, OF LEXINGTON, MISSISSIPPI, ASSIGNOR OF ONE-HALF TO SAMUEL D. GIVIN, OF SAME PLACE.

RAILROAD-TIE.

SPECIFICATION forming part of Letters Patent No. 445,274, dated January 27, 1891.

Application filed July 16, 1890. Serial No. 358,929. (No model.)

To all whom it may concern:

Be it known that I, HARRY IRWIN JEFFERS, a citizen of the United States, residing at Lexington, in the county of Holmes and State of Mississippi, have invented new and useful Improvements in Railway-Ties, of which the following is a specification.

My invention relates to an improvement in railway-ties; and it consists in the construction and arrangement of parts hereinafter described, and pointed out definitely in the claim.

The object of my invention is to provide a tie with respect to which the rails may be readily attached and detached and which may be utilized without the application of spikes. I attain this object by the construction illustrated in the accompanying drawings, wherein like letters of reference indicate corresponding parts in the several views, and in which—

Figure 1 is a perspective view of my tie, and Fig. 2 is a longitudinal section through the center.

25 In the drawings, A represents the tie, preferably formed of metal, having a rectangular opening in its center, as at B.

The upper face of the ends of the tie is cut away or reduced, as at C, the inner portion 30 being cut diagonally inward, forming tongue D, having its upper edge projecting over the reduced portion. In the end portions are formed longitudinal recesses or channels E, extending through the reduced portion and the central 35 part into the central opening B. The outer part of the recess has an open top, thereby forming a shoulder e. Slidingly arranged in the recesses E are clamping-bars or securers F, formed to snugly fit in the recesses, and 40 having reduced inner ends f, which pass through to the opening B. These ends have vertical slots therein, through which is adapted to pass a suitable wedge G for locking the bars in place. The outer ends of the bars F

have a gripping-tongue H thereon, with an 45 inclined edge to form a gripping-surface corresponding to the one on the tie, which is oppositely inclined.

In operation the rails are placed in position, the inner flanges projecting under the tongues 50 D. The bar F is then drawn in by forcing down the wedge and the tongue H forced over the opposite flange of the rail. The rails are thereby securely held in place, and by withdrawing the wedge they may be readily 55 released.

I am aware that many minor changes in the construction and arrangement of the parts of my device can be made without in the least departing from the nature and principle of 60 my invention.

Having thus described my invention, what I claim as new, and desire to secure by Letters Patent, is—

A railway-tie consisting of a metal bar 65 formed with a rectangular opening in its center and flat cut-away outer upper faces, the inner end walls of the cut-away portions being inclined inwardly to form gripping-tongues extending entirely across the tie, and 70 having longitudinal channels in the cut-away portions terminating at their inner ends in slots beneath the tongues and leading into the central openings, the sliding clamping-bars in the channels, their ends extending 75 through the slots and formed with vertical apertures, the outer ends of the bars formed with enlarged gripping-tongues, and wedges passing through the apertures in the bars and impinging against the end walls of the central opening, substantially as described.

In testimony whereof I affix my signature in presence of two witnesses.

HARRY IRWIN JEFFERS.

WILL SMITH,
E. D. MCBEE.

Correction in Letters Patent No. 445,274.

It is hereby certified that the name of the assignee in Letters Patent No. 445,274, granted January 27, 1891, upon the application of Harry Irwin Jeffers, of Lexington, Mississippi, for an improvement in "Railroad-Ties," was erroneously written and printed "Samuel D. Givin," whereas said name should have been written and printed *Samuel D. Gwin*; and that the said Letters Patent should be read with this correction therein that the same may conform to the record of the case in the Patent Office.

Signed, countersigned, and sealed this 17th day of February, A. D. 1891.

[SEAL.]

CYRUS BUSSEY,
Assistant Secretary of the Interior.

Countersigned:

C. E. MITCHELL,
Commissioner of Patents.
